Ill., assignors to B. F. Gump Co., Chicago, Ill.,
a corporation of Illinois

Application March 12, 1936, Serial No. 68,494

1 Claim. (Cl. 209—332)

This invention relates to a gyratory sifter and concerns itself with novel supporting means for causing the sifter to travel in a circular path.

It is an object of the present invention to support the sifter or screen box independently of the operating means so that the weight thereof will not bear upon the operating parts.

It is a further object of this invention to provide a supporting structure for the screen box involving wobbling posts in which such posts are maintained properly aligned.

With these and other objects in view which will become apparent in the following description, this invention comprises the novel structure and combinations of parts hereinafter described and more particularly pointed out and defined in the appended claim.

In the accompanying drawings which illustrate a preferred form of this invention and in which similar reference numerals refer to similar features in the different views:

Figure 1 is a part elevational and part sectional view of a gyratory sifter involving this invention.

Figure 2 is an enlarged sectional view of the upper end of a wobble post.

Figure 3 is an enlarged fragmentary sectional view through the base and the lower end of a free wobble post.

Figure 4 is an enlarged fragmentary sectional view through the base and the lower end of one of the controlled wobble posts.

Figure 5 is a fragmentary sectional view through the base taken substantially upon the line V—V of Figure 4, showing parts in elevation.

Figure 6 is a fragmentary plan view of the sifter chassis, showing in dotted lines the gyratory movement.

As shown on the drawings:

On the drawings, there is shown a sifter or screen box 1 which may be of any suitable construction. It is supported upon two pairs of wobble posts 2 and 3 which in turn are supported on a metal base 4. The metal base has a channel 5 at one margin in which a rockable shaft 6 is journaled by means of bearings 7 which are located in lubricant chambers 8 formed in the ends of the channel 5 which is closed by a cover strip 4a provided with suitable apertures 8 through which the wobble posts 2 extend. Oil seals 9 may also be placed in suitable recesses in the inner walls 10 of the lubricant chambers for retaining the lubricant against movement on the shaft 6.

The wobble posts 2 have yokes 2a at their lower ends. The bifurcations of these yokes are of such a size as to readily fit over the shaft 6. Bolts or pins forming trunnions 11 extend through the arms of the yokes and shaft 6 for connecting the posts to said shaft. The pins 11 are preferably anchored in position by means of dowel pins 12 which extend through the shaft 6 and pins 11. Each wobble post 2 may be provided with a groove 13 for receiving an anchor ring 14 upon which a flexible hood or stocking 15 is secured. The hood 15 is also fastened to the top of the base by means of a ring 16, as shown. The purpose of the hood is to prevent dust from entering the lubricant chambers.

The upper ends of the two wobble posts 2 are formed with sockets 17, as shown in Figure 2. A bearing 18 having a parti-spherical bearing recess is secured in the bottom of each socket. A spherical bearing 19 in the form of a ball is located in each socket and seated in the bearing recess of its bearing 18. A bearing ring 20 is preferably threaded in the upper end of each socket and is fashioned to fit the curved surface of the bearing ball 19. The sockets 17 may be enlarged above the bearings 18, as indicated at 21, to provide a lubricant chamber.

Suitable metal pads 22 are secured to the spherical bearings 19. These pads are preferably provided with bosses 23 carrying screws 24 threaded into the spherical bearings. The bosses 23 and the socket heads of the posts 2 are also provided with grooves 24 for receiving rings 25 to which a flexible stocking 26 is secured to exclude dust from the bearing.

The two wobble posts 3 are provided at their lower ends with spherical bearings 27, as shown in Figure 3. These spherical bearings 27 are located in suitable bearing boxes 28 supported and secured upon shelves 29 extending from a side wall of the base below the top thereof, the top of the base being cut away to receive the bearing boxes. Within each bearing box 28, there is a bearing 18, as before described, for supporting the spherical bearing 27. Likewise, the bearing boxes are enlarged as indicated at 21 to provide a lubricant chamber. A flexible hood or stocking 30 surrounds each post 3. The hoods are anchored to the top of the base by rings 31 and to the posts 3 by rings 32 seated in grooves 33 in the posts. The upper ends of the two wobble posts 3 are secured to the pads 22 in the same manner as the wobble posts 2, as shown in Figure 2. Angle members 34 connect the pads of the posts 2 with the pads of the posts 3. These angle mem-

bers serve as a part of the chassis for the screen box.

The chassis further comprises the transverse angle bars 34a to which there is secured a spider 36 upon which there is a crank pin 37. This crank pin 37 has a ball bearing connection 38 with a horizontal fly wheel 39. The fly wheel 39 is secured upon a vertical shaft 39a that extends into a gear box 30. A motor 41 which is mounted upon the base drives a belt 42 which surrounds a pulley 43 secured upon a shaft 44 extending into the gear box. The manner of gearing the shaft 44 to the shaft 39a in the gear box has not been illustrated, since it may be effected in any well-known manner.

It will be noted that the crank pin 37 is eccentric to the axis of the shaft 39a that supports the fly wheel, which constitutes means for rotating the crank pin 37. Consequently, when the fly wheel is rotated, the crank pin 37 will rotate in a circle and impart a gyratory movement to the screen box 35 which is supported and secured upon the angle bars 34 and 34a. The weight of the screen box is supported by the four wobble posts and little, if any, weight thereof is transmitted through the crank pin 37.

The chassis is more clearly shown in Figure 6, and it will be noted that additional transverse angle bars 34b are located between the angle bars 34 and 34a. The ends of these angle bars are secured to longitudinally extending angle bars 34c. The angle bars 34c have upstanding flanges that form the outer edge of the chassis and thus provide a depressed seat for the sifter box 1. At the ends of the angle bars 34c are transverse angle bars 34d that confine the ends of the sifter box, which may be bolted or secured in said seat in any approved manner.

In the operation of the machine, the rotation of the fly wheel 39 will carry the crank pin 37 around in a circle and impart a gyratory movement to all parts of the sifter box in contradistinction to prior art devices in which only the forward portion of the sifter box is rotated and the rear part is reciprocated.

During the gyratory movement of the sifter box, the wobble posts 2 and 3 are constrained to move in proper alignment, that is, one cannot move in one direction and another in the opposite direction, due to the shaft 6 which rocks or oscillates in its bearings and causes the two controlled posts 2 to move in alignment. The posts 3 must likewise move in unison in the same direction as shown in Figure 6. It will be appre-

ciated that the posts 2 can pivot on the pins 11 and can rotate or rock the shaft 6 which forms the controlling element for causing the wobble posts to move in unison and alignment.

While the throw of the crank pin 37 is short as illustrated, it is contemplated that a spider with a crank pin having a longer or shorter throw may be used as desired.

The provision of the lubricant chambers maintains the posts properly lubricated during operation and the hoods or stockings protect the lubricated parts from dirt and dust, whereby a highly efficient apparatus is obtained.

It is realized that attempts have heretofore been made to use wobble posts for supporting a sifter, but no proper means were provided therein for controlling the movements of the posts, and in most cases the weight of the sifter box was sustained by the crank pin.

From the foregoing, it will be appreciated that a novel supporting means for a sifter box has been invented that always supports the weight of the sifter box and relieves the operating crank from carrying any of the load.

We are aware that many changes may be made and numerous details of construction may be varied through a wide range without departing from the principles of this invention, and we, therefore, do not purpose limiting the patent granted hereon otherwise than is necessitated by the prior art.

We claim as our invention:

A gyratory sifter comprising a sifter table, means to drive said table, a base, a rocker shaft journaled in bearings on said base, a first pair of wobble posts in longitudinally spaced relation, each of said posts being connected at its upper end to said sifter table by ball joint and socket means, each of the wobble posts at its lower end being connected to said rocker shaft by means constraining said posts to rocking movement with said shaft and pivotal movement relative to said shaft about an axis extending transversely of said shaft, and a second pair of wobble posts in longitudinally spaced relation and each connected at its upper end to said sifter table by a ball joint and socket means, and having a universal pivotal connection at its lower end with said base, said wobble posts constituting supporting means for said sifter table whereby said driving means for said sifter table whereby said driving means are substantially relieved of the weight of said table.
